UNITED STATES PATENT OFFICE

JOHN B. MILLER, OF KNOXVILLE, TENNESSEE, ASSIGNOR TO KNOX STOVE WORKS, OF KNOXVILLE, TENNESSEE, A CORPORATION OF TENNESSEE

DESIGN FOR A CIRCULATING HEATER

Application filed May 12, 1932. Serial No. 43,788. Term of patent 7 years.

To all whom it may concern:

Be it known that I, JOHN B. MILLER, a citizen of the United States, residing at Knoxville, in the county of Knox, State of Tennessee, have invented a new, original, and ornamental Design for a Circulating Heater, of which the following is a description, reference being had to the accompanying drawing, forming a part thereof.

In the drawing:

The figure is a perspective view of the heater, showing my new design.

I claim:

The ornamental design for a circulating heater, as shown.

In testimony whereof, I affix my signature.

JOHN B. MILLER.
